UNITED STATES PATENT OFFICE.

LUCIUS J. RICHARDS, OF SPRINGFIELD, MASSACHUSETTS.

VOLUMETRIC GAS-GOVERNOR.

SPECIFICATION forming part of Letters Patent No. 730,047, dated June 2, 1903.

Application filed March 12, 1902. Serial No. 97,860. (No model.)

To all whom it may concern:

Be it known that I, LUCIUS J. RICHARDS, a citizen of the United States of America, residing at Springfield, in the county of Hampden and State of Massachusetts, have invented new and useful Improvements in Volumetric Gas-Governors, of which the following is a specification.

This invention relates to volumetric movement gas-governors adapted to be applied to the outlet of a gas-meter or between the latter and the supply-pipe leading to the place or places of gas consumption, said governor being likewise adapted to be used with other gaseous substances for regulating the flow thereof; and the invention consists in the peculiar construction and arrangement of the devices of said governor, the object being to provide an improved device of this class which 20 provides means for variably adjusting the gas-flow to obtain an unvarying delivery under varying pressure from the source of supply.

In the drawings forming part of this application, Figure 1 is a front elevation of the upper portion of an ordinary gas-meter, showing in the tubular outlet thereof in side elevation my improved governor in operative position and the means employed for securing the same in said outlet. Fig. 2 is an enlarged longitudinal sectional view of said tubular outlet and a like sectional view of my improved governor, illustrating the several structural elements thereof. Fig. 3 is a transverse sectional view on line 3 3, Fig. 2.

Referring to the drawings, *a* indicates the meter-outlet, and *b* a pipe connecting the same with the usual gas-pipes of a building and secured to said outlet by a nut *c*. The 40 lower end of said pipe *b* has an annular groove *o*, which receives an annular flange on the lower end of the governor-case *e*, as shown, whereby the latter is held in an upright position in said pipe *b*, as shown in Fig. 2, the said lower end being freely open to permit gas from the meter to enter therein. Said 45 governor comprises the outer metallic case *e* of the tapering form shown, having in the sides thereof, near its upper end, several openings *i*, through which gas may escape therefrom in predetermined volume, as below set forth. On the upper end of said case *e* is a movable

cap *f*, in the sides of which are a series of openings *x*, (see Fig. 3,) which upon turning the cap are brought to register with the said openings or gas-passages *i* in the case or to more or less reduce the area of said passages, whereby more or less gas is allowed to pass from the governor outwardly, according to the quantity or pressure desired at the burners, 55 thereby positively limiting the quantity of gas which can pass through the governor under a given pressure from the mains. Near the upper end of said case *e* is fixed a cone-shaped perforated diaphragm *m*, having perforations 60 through the top thereof, as shown, for the passage of gas from below after passing a suspended valve *n*, which is automatically movable vertically, the upward movement thereof being due to any sudden increase of gas-pressure 65 in the case *e*, whereby the area of the gas-passage between the inner wall of said diaphragm *m* and the adjoining pending borders of said valve *n* is reduced, thereby effecting a 70 reduction of the volume of gas passing through the perforations shown in the upper wall of 75 said diaphragm *m*. The said valve *n* is hung on and guided vertically by the stem *r*, so that it may automatically assume such positions within the diaphragm *m* as is demanded by 80 the flow of gas under varying pressures to insure a steady delivery through the governor.

A tapered funnel *s* is forced into the lower end of the casing *e*, said funnel pointing upward and its upper end being open. This 85 funnel is stationary in the casing, and over its upper end is located an inverted-cup-shaped valve *t*, whose tapered sides fit closely the tapered sides of the funnel *s* and completely closes the open end of the latter when 90 no gas flows through the meter. This valve *t* must be raised by the flow of gas through the funnel, and to the end that it may be held in axial alinement with said funnel it is provided with a mixed tubular extension *v*, into 95 which there enters the end of a vertically-depend ing guide-wire *w*, whose opposite end may be secured in any convenient manner to the funnel *s*. A weight *z* may be suspended from the under side of the valve *t* to adapt 100 the devices to an abnormal pressure of gas. The said devices, consisting of the diaphragm *s*, the valve *t* and its guide-wire *w*, and variable weight *z* in the lower end of said case,

may when the gas-flow is of substantially unvarying force be dispensed with, if desired.

Having thus described my invention, what I claim, and desire to secure by Letters Patent of the United States, is—

1. A gas-governing device consisting of a tapered case located in the outlet-pipe of a meter, the inlet end of said case being open and fitting tightly said outlet, said case having a closed upper end provided with one or more openings; a rotatable member on said case having perforations therein adapted to register with the openings in the upper end of the case; a tapered diaphragm in the case near the closed end thereof, there being one or more apertures in the diaphragm; a vertically-movable valve extending axially of said diaphragm, actuated by the flow of gas to vary the area of the gas-passage between its border and the inner wall of said diaphragm.
2. A gas-governing device consisting of a tapered case located in the outlet-pipe of a meter, the inlet end of said case being open and fitting tightly said outlet, said case having a closed upper end provided with one or more openings; a rotatable member on said case having perforations therein adapted to register with the openings in the upper end of the case; a tapered diaphragm in the case near the inlet end thereof having a central aperture therein, a vertically-movable tapered valve fitting closely over the upper end

of said tapered diaphragm and adapted to be lifted by the flow of gas, together with a weight located axially of said diaphragm and suspended from the vertically-movable valve. 35

3. A gas-governing device consisting of a tapered case located in the outlet-pipe of a meter, the inlet end of said case being open and fitting tightly said outlet-pipe, the upper end of said case being closed and provided with one or more openings; a rotatable member on said case having perforations therein adapted to register with the openings in the upper end of the case, a tapered diaphragm 45 in the case near the upper end thereof, having one or more apertures therein; a vertically-movable valve suspended within said diaphragm and actuated by the flow of gas to vary the area of the passage between its borders and the walls of said diaphragm; a second tapered diaphragm located near the lower end of the case and having an aperture in the upper end thereof; a vertically-movable tapered valve fitting closely over the upper end 50 of said second diaphragm and adapted to be lifted by the flow of gas, together with a weight located axially of said diaphragm and suspended from the last-named valve. 55
